TRAY FOR HAIR STYLIST'S IMPLEMENTS

Ralph A. Gonzalez, 2114 Heloise Way,
Placentia, Calif. 92670

Filed July 18, 1973, Ser. No. 380,454

Term of patent 3½ years

Int. Cl. D28—03

U.S. Cl. D86—10 A

FIG. 1 is a perspective view of a tray for hair stylist's implements showing my new design looking in the direction of the top, front, and left side thereof;

FIG. 2 is a perspective view looking in the direction of the bottom, rear, and right side thereof;

FIG. 3 is a cross sectional view taken along the line 3-3 of FIG. 1; and

FIG. 4 is a cross sectional view taken along the line 4-4 of FIG. 1.

I claim:

The ornamental design for a tray for hair stylist's implements, as shown.
